UNITED STATES PATENT OFFICE.

GEORGE PRESCOTT, OF MINNEAPOLIS, MINNESOTA.

FURNACE.

No. 909,218.

Specification of Letters Patent.

Patented Jan. 12, 1909.

Application filed December 23, 1907. Serial No. 407,817.

To all whom it may concern:

Be it known that I, GEORGE PRESCOTT, a citizen of the United States, residing at Minneapolis, in the county of Hennepin 5 and State of Minnesota, have invented certain new and useful Improvements in Furnaces; and I do hereby declare the following to be a full, clear, and exact description of the invention, such as will enable others skilled in the art to which it appertains to 10 make and use the same.

My invention relates to furnaces and especially those that are used in connection with boilers for generating steam, and has 15 for its object to provide certain improvements whereby the combustion of the furnace is rendered more complete, thereby accomplishing two important results, to-wit, economy in the use of fuel and the burning 20 of the smoke.

To the above ends the invention consists of the novel devices and combinations of devices hereinafter described and defined in the claims.

25 In the accompanying drawings which illustrate the invention, like characters indicate like parts throughout the several views.

Referring to the drawings, Figure 1 is a view showing, in vertical longitudinal section, a furnace with my invention applied thereto and showing in full side elevation a horizontal boiler located in the furnace; and Fig. 2 is a transverse vertical section taken on the line $x^2 x^2$ of Fig. 1, but with 35 some parts broken away.

The numeral 1 indicates the exterior brick-work or masonry of the furnace, within which is placed a horizontal boiler 2, shown as of standard construction. Instead 40 of the boiler shown a water tube boiler of any suitable or approved construction may be employed.

The intermediate portion of the boiler 2 overlies a vertical transversely extended fire 45 wall 3, from which a fire arch 4 projects forward and assists in forming a primary combustion chamber. The fire arch 4 terminates considerably short of the front wall of the main brick-work 1, so as to leave a 50 large draft passage 5 at the front of the furnace; and just above this passage 5 is an upper or secondary fire arch 6 that protects the front portion of the boiler from the direct action of the products of combustion 55 that pass upward through the passage 5, and serve to deflect rearward said products

of combustion, as indicated by arrows marked on Fig. 1. The grates 7 are secured in the usual way below the arch 4. The products of combustion or flames pass 60 rearward from the flame passage 5 to the rear end of the boiler to-wit: into the secondary combustion chamber, thence through the usual flues thereof (not shown) into the smoke box 8, and thence out through the 65 stack 9. The fire wall 3 is formed with a vertical transversely extended air chamber 10 which has an air induction port 11, which, as shown, opens through one of the side walls of the brick-work 1. At its upper 70 portion the air chamber 10 opens into the primary combustion chamber of the furnace below the arch 4 through a multiplicity of air passages 12, preferably formed in the brick-work of the side wall. 75

Located within the air chamber 10 is a radiator, preferably formed by a pipe coil or alternated loop 13, one end of which is connected, by a steam supply pipe 14, to the dome of the boiler 2. In the steam supply 80 pipe 14 is a valve 15. The other extremity of the pipe coil 13 extends outward through the air induction port 11 and is connected, by a pipe 16, to a perforated nozzle pipe 17, which latter, as shown, is passed through 85 the rear wall of the brick-work 1 and extends transversely of the secondary chamber 1^a just below and at the rear of the rear end of the boiler 2. The pipe 16 is provided with a valve 18, and the lower extremity of 90 the coil 11 is provided with a valve 19. The valve 19 should be normally closed as it serves only as a drain cock to draw off condensed water from the coil 13 and pipes connected thereto. The valve 18 should be 95 opened or closed according to whether or not it is desired to use the nozzle pipe 17 to precipitate the soot. The valve 15 should be normally opened so that steam will be kept within the coil 13. 100

When the parts are thus adjusted and the furnace is in action, the heat radiated from the coil 13 superheats the air in the air chamber 10, and the said air, of course, is also heated to a certain extent by the direct 105 radiation of heat through the fire wall 3. The air thus drawn into the chamber 10 through the air induction port 11 will be first superheated by the means just noted and will be drawn into the primary combustion chamber of the furnace through the 110 ports or passages 12 at the rear of said com-

bustion chamber, and will be drawn along directly under the arch 4, where it will greatly intensify the draft and very greatly increase the intensity of the combustion by 5 the supply of oxygen which it affords. It is, of course, evident that fresh hot air which effect in producing complete combustion. chamber will increase the combustion to a very much greater extent than cold air. It 10 is also evident that the air is introduced where it will have the most advantageous effect in producing complete combustion. In starting the furnace the greatest difficulty is experienced in effecting such 15 complete combustion that no smoke will escape from the furnace. To prevent the escape of smoke at such times the valve 18 is opened so as to cause escape of a spray of steam through the products of combustion just before they enter the flues of the boiler. This 20 spray of steam will precipitate all soot or incompletely burned particles and thus abate the smoke nuisance. Except when starting the furnace, however, this steam spraying device is not necessarily used.

It is further important to note that the steam delivered to the nozzle pipe 17 passes first through the coil 13 where the steam will be superheated by the heat radiated from 30 the furnace into the air chamber 10. This superheated steam will not check, to any perceptible extent, the intensity of the combustion at the point where it is applied.

A furnace may be constructed as above 35 described at small cost and will accomplish the primary object of this invention above set forth.

What I claim is:

1. In a furnace, the combination of a furnace chamber, and a boiler located therein, 40 a fire wall dividing said chamber into a primary and secondary combustion chamber; a fire arch extending forwardly and into the primary combustion chamber from the top 45 of said fire wall but terminating short of the front wall of the furnace chamber, a second fire arch extending rearwardly from the front wall of the furnace chamber, and adapted to overlap the front portion of the

first mentioned fire-arch, said second arch 50 being located above the plane of and at a distance from said first mentioned arch, and also underlying and closely engaging the forward lowermost portion of the boiler, said fire-wall having an air chamber therein, an induction port and a multiplicity of air escape ports in said air chamber, the latter opening into the primary combustion chamber below the first mentioned fire-arch, and a steam pipe coil located in said air 60 chamber for super-heating the air passing into the primary combustion chamber, substantially as described.

2. In a furnace, the combination of a furnace chamber, and a boiler located therein, 65 a fire wall dividing said chamber into a primary and secondary combustion chamber; a fire arch extending forwardly and into the primary combustion chamber from the top of said fire wall but terminating short of 70 the front wall of the furnace chamber, a second fire arch extending rearwardly from the front wall of the furnace chamber, and adapted to overlap the front portion of the first mentioned fire-arch, said second arch 75 being located above the plane of and at a distance from said first mentioned arch, and also underlying and closely engaging the forward lowermost portion of the boiler, said fire-wall having an air chamber therein, an induction port and a multiplicity of air escape ports in said air chamber, the latter opening into the primary combustion chamber below the first mentioned fire-arch, and a steam pipe coil located in said air chamber 80 and connected to said boiler, and a steam pipe extending from said steam pipe coil and terminating in a nozzle pipe, located in position to discharge into the rear portion of said secondary combustion chamber on a line between the two fire arches, 85 substantially as described.

In testimony whereof I affix my signature in presence of two witnesses.

GEORGE PRESCOTT.
